PRINTING TELEGRAPH TRANSMITTER

Karl Weber, Berlin-Tempelhof, Germany, assignor to C. Lorenz A. G., Berlin-Tempelhof, Germany, a corporation of Germany

Application January 25, 1936, Serial No. 60,835
In Germany January 30, 1935

21 Claims. (Cl. 178—23)

This invention pertains to automatic telegraph systems and apparatus and more particularly to printing telegraph apparatus arranged for inclusion at a station unattended by an operator.

The principal object of the invention is to provide apparatus which will send automatically in response to operation of a single key code signal combinations representing certain prearranged information.

A corollary object is to provide a multi-code sending key operating to send a plurality of code signal combinations in response to each operation of the key.

15 A further object is to provide signal responsive mechanism by which code signal combinations representative of the identity of a called station may be transmitted in response to depression of a key at a remote controlling station.

20 A feature of the invention is the provision of mechanism for locking all keys in a keyboard containing a key effective for each depression to transmit code signal combinations so that during the time interval required for the transmission of such plurality of code signals, the operation of any other key will be prevented.

A better understanding of the invention may be had from the following description, taken in conjunction with the accompanying drawing where-

30 in is shown an expanded perspective view of printing telegraph apparatus for sending and receiving auxiliary messages.

The operating parts of a structure according to this invention comprise a keylever 1 controlling a set of five code bars 2, each of which controls one of a set of five code latches 3 which in turn latch or leave operable individually five code transmitting levers 4. A plurality of key levers, such as 1, engage a universal bar 5 connected to a pull bar 6 having a hook end engaging a bell crank lever 7 which in turn engages a clutch trip lever 8. Clutch trip lever 8 controls the engagement of clutch 10 through which power is communicated from power shaft 9 to drive start-stop shaft 11 which carries cam barrel 12 adapted to release serially the five code transmitting levers 4 and thereby to control in code manner five code transmitting contacts 13. A latch lock bail 14 is biased by a spring 43 and is controlled by a latch lock cam 15 on shaft 11 and controls a rocking bar 16 which, through a bell crank lever 17, controls a sliding bar 18 which normally blocks the path of movement of a pull bar stop member 21 to hold it out of the path of pull bar 22. Sliding bar 18 when operated is engaged by latch 19 and thus

held out of the path of pull bar stop member 21.

Also included in the structure is a case shift member 23 shown in its letter case position and cooperating with a case shift latch 24 which engages and restrains key operating lever 25. Pull bar 22 engages one end of pivoted pull bar rocking lever 26 whose other end operates latch 27 in a manner to withdraw latch 27 from power slide 28, thus permitting slide 28 to be moved upwardly by key operating lever 25, which at the same time will depress a multi-code key lever 29. Pivoted on key lever 29 is an operating latch 30 adapted to operate a multi-code normal latch 31 in response to movement of key 29 to release rocking lever 32 which carries pawl 33 operating upon teeth of ratchet wheel 34 through pawl tooth 35. Retaining latch 36 engages normal latch 31 to retain key 29 in its operated position independently of lever 25. Key lever 29 engages code latch control bar 37 which in turn engages all code latches 3 and restrains them from interfering with the operation of code levers 4 when code drum 39 controls levers 4 by reason of off-normal positions of code drum 39 attained as a result of step-by-step rotation of code drum shaft 38 by its affixed ratchet 34. Further detail of the operating parts together with the manner of their operation is as follows:

A plurality of key levers 1 each having a key 50, comprising a keyboard sufficient to transmit severally letters of the alphabet, figures, and other characters are provided in the manner of any telegraphic transmitter, and to this assembly of single-code key levers is added according to this invention the multi-code key lever 29. Each 35 of the single code key levers 1 engages directly five code bars 2 none of which is directly engaged by the multi-code key lever 29, and by the depression of any key lever 1 the code bars 2 are set longitudinally in sliding manner to right and left in 40 code combinations, thus operating the five code latches or contact controlling members 3, pivoted at 51 so that a code bar 2 positioned leftwardly as viewed in the figure will rotate its associated code latch 3 clockwise to disengage its upper end from 45 its corresponding code transmitting lever 4 while code latches 3 positioned rightwardly at the lower end and leftwardly at the upper end will engage respectively their code transmitting levers 4 to prevent operation thereof by cams of cam barrel 50 12, thus setting up a combination of elements adapted to transmit a code signal from code transmitting contacts 13. Similar to the manner disclosed in U. S. Patent No. 1,965,572 issued to 55 C. W. Burcky et al. (having special reference to

Fig. 6 of the patent) depression of any key lever 1 also will engage and depress universal bar 5 rocking it upon its pivot 52 so that through its connection at 49 it pulls the pull bar 6, whose hook end 53 rotates bell crank 7 upon its pivot 54 and lever 6 by a lug 55 engages a fixed member 56 which imparts a downward motion to bar 6 and disengages hook 53 from bell crank lever 7, thus liberating bell crank 7 to return to normal under tension of spring 57. This momentary action of bell crank 7 has caused a similar action in clutch trip lever 8 pivoted at 58 which momentarily has removed its clutch engaging finger 59 from clutch 10, permitting clutch 10 to engage its two members together whereby power shaft 9 begins rotation of start-stop shaft 11. Both of parts 7 and 8 are restored by spring 57 while universal bar 5 and pull bar 6 also are restored by a spring not shown. The start-stop shaft 11 rotates once and transmits a code signal of impulses by contacts 13 controlled in code manner by such levers 4 as are not restrained by latch 3, and at the end of one cycle of rotation, finger 59 again is engaged by clutch 10 and causes clutch 10 to disengage its members from each other, thereby stopping stop shaft 11. The code thus transmitted to line is effective upon a remote receiver having a case shift member 23 responsive to a specific predetermined code, and having a pull bar 22 also responsive to another predetermined code if that pull bar 22 is not obstructed by stop member 21. Other codes operate type bars and function members in the printer at the responsive station.

The description above discloses the operation of a single-code key lever 1 and the resultant transmission to a line circuit of a single code under control of cam barrel 12 in response to a key lever 1.

Operation of the multi-code key lever 29 results in transmission to the same line channel by operation of the same contacts 13 but under control of cams or contact controlling members on code drum shaft 38 in response to key lever 29 instead of under control of latches 3. Manual depression of key 60 rocks key lever 29 upon its pivot 61 against the biasing action of spring 40 and lifts the extremity 63 which engages arms 64 and 65, operating bell crank lever 7 by means of arm 65 to trip clutch 10 in manner similar to that above described, with the further provision that members 7 and 8 are retained in their operated position so that finger 59 will not be engaged by clutch 10 in its successive rotations. Also, arm 64 operates bar 37 pivoted at 66 to move bar 37 against the upper ends of all code latches 3, thereby disabling all code latches 3 from control of code transmitting levers and also moving all code bars 2 to their left-hand operating positions, although as herein disclosed, these bars may not be directly engaged by key lever 29. Key lever 29 also by its downward movement at the left-hand side of its pivot 61 draws member 68 on operating latch 30 into engagement with member 69 on normal latch 31, thereby rocking the latch 31 on its pivot 71, withdrawing tooth 72 of latch 31 from cam 73, and withdrawing tooth 74 of latch 31 from rocking lever 32. Latch 36 pivoted at 76 upon key lever 29 now is operated by its spring 75 to move its upper portion 41 into a notch 42 on the lower end of normal latch 31 whereby key lever 29 is mechanically locked in its depressed position and will remain so locked as long as normal latch 31 remains rotated counterclockwise as described.

Simultaneously with the operations just described and while the finger of the operator still holds key 60 depressed, clutch 10 begins the movement of shaft 11 which rotates cam 15 to release the latch lock bail 14 pivoted at 77 whose counterclockwise motion under the action of spring 43 releases rocking lever 32 whose spring 78 rocks the lever 32 upon its pivot 79 to lift pawl 33 which steps ratchet 34 and cam 73, thereby stepping the cam notch of cam 73 out of alignment with the tooth 72 of normal latch 31 and estopping the return of latch 72 into normal position until such time as cam 73 shall have traversed successive steps to complete its cycle of rotation into its normal position. The face of cam 73 now holds normal latch 31 locked, which in turn holds retaining latch 36 and thereby holds key 60 locked in depressed position until code drum shaft 38 shall have completed a full cycle. The actions described since depression of key 60 by the operator have taken place almost simultaneously, and the operator's finger now is not required further upon key 60. It will be noted that the locking of key 60 downward has locked extremity 63 upward, which has locked bar 37 outward or rightward, and which has in turn locked the five code latches 3 in clockwise position and has locked the five code bars 2 in their left-hand positions so that no key 1 can be depressed since the inability of code bars 2 to yield to any key lever 1 will estop all key levers 1 from depression, and the operator having depressed key 60 is in turn estopped from depressing any key 1 to interfere with signals in the line during the extended period of transmission responsive to key 60 until that period of transmission is completed.

Transmission of the plurality of codes now proceeds as follows: With trip lever 8 locked in clockwise position, shaft 9 rotates shaft 11 and cam barrel 12 continuously by means of clutch 10 and operates levers 4 cyclically and in repeated cycles, the coded nature of the repeated cycles being determined by the control-blocking or non-blocking of the levers 4 by cams in the code drum 39 in lieu of the control-blocking by latches 3. At each revolution of shaft 11, cam 15 lifts and lowers bar 14 which rocks rocking lever 32, which by pawl 33 steps code drum shaft 38 one step to present a succeeding set of cams upon code drum 39 to control the levers 4. When the entire series of code signals has been transmitted, the last rocking movement of lever 32 will step code drum shaft 38 into normal position, and at the end of the last code, cam 15 will lift bar 14 to rock the lever 32 counterclockwise, whereupon tooth 72 being opposite the notch of cam 73 and the left-hand end of lever 32 now being below tooth 74 of normal latch 31, the normal latch 31 under tension of its spring 81 will resume its normal position as shown, thereby releasing retaining latch 36 and releasing key lever 29, permitting key 60 to rise under the influence of spring 40, thereby depressing the extremity 63 and permitting arms 64 and 65 to fall, the action of arm 65 permitting operation of clutch trip lever 8 by its spring 57 to pass clutch engaging finger 59 into engagement with clutch 10 to disengage power shaft 9 from start-stop shaft 11, thereby stopping the shaft 11. The fall of arm 64 has removed bar 37 from code latches 3, thereby unlocking code bars 2 and keys 1.

During this operation at the transmitting station, the operation at the receiving station has been normal in all details with the printer responding to the several codes serially sent, in the

same manner that it would respond to the same codes if sent by successive depression of a plurality of keys 1. It is customary in telegraphic transmitters of the nature herein considered to provide 5 a key 1 for each possible combination in the system of codes for which the transmitter is being used. To such a keyboard this invention adds a multi-code key 60 to transmit upon each operation thereof a plurality of code signals which 10 necessarily therefore must be selected among the code signals for which individual keys already have been provided.

In providing for the transmission of station 15 identifying signals responsive to code signals received over a transmission line, the structure of this invention uses the equipment already provided and described above for the transmission of the multicode message by a single multi-code key and accomplishes this result by provision of 20 apparatus to depress key 60 automatically and mechanically in response to the receipt of a predetermined code signal or of a plurality of code signals in predetermined order.

It is well understood that type printing tele- 25 graphs using type bars and pull bars for operating type bars are provided normally with signal responsive notched code bars which jointly select a single pull bar which then may be operated by a motor driven power bail. Such a 30 pull bar is shown at 22 and such a power bail is shown at 20. In such receiving printers there is provided also a case shift member which assumes one mechanical position in response to a single code signal and retains that mechanical position 35 throughout transmission of all code signals intended to print letter characters, then changes its mechanical position in response to a single code signal and retains the changed position throughout all codes intended to print figures 40 and characters. Such a member is shown at 23 and it is shown in its "letters" or unshift position.

In response to "figures" or shift code signal, the member 23 changes to its downward position, thereby permitting spring 85 to rock a code shift 45 latch 24 upon its pivot 94 to withdraw its tooth 96 from engagement with the key operating lever 25, thereby unlocking lever 25 to be responsive to its spring 87 subject to the unlocking of power slide 28 by latch 27 in response to rotation of pull 50 bar rocking lever 26 by pull bar 22. Members 23 and 24 have been operated in response to a received code signal for "figure shift," a received code signal identified with pull bar 22 will cause the response of code bars 105, in the manner disclosed in U. S. Patent No. 1,745,633 issued to S. Morton et al., to select lever 22 and release it for operation by its spring 88 into position to be engaged by power bail 20. Pull bar 22 accordingly moves into path of power bail 20, and is engaged by a rising movement of power bail 20, and is drawn upward, thereby rotating rocking lever 26 and depressing arm 91 of latch 27, withdrawing the tooth of latch 27 from power slide 28 which is a member sliding upon two studs at 92 55 and 93 and which is engaged and depressed by power bail 20 in the depressed or downward position of that power bail. Power bail 20 being now in elevated position and slide 28 being now unlocked by latch 27, the spring 87 acts to rock 60 the key operating lever 25 upon its pivot 84 to depress key 60 and to rock the lever 29, which acts as above described to trip the clutch 10 and to set the cam 73 off normal so that key lever 29 becomes locked with key 60 in depressed position. Slide 28 has been lifted by spring 87

associated with lever 25, and functions as a means for restoring lever 25. Upon the immediately subsequent depression of power bail 20, the pull bar 22 is urged downwardly by its spring 88 to release the rocking lever 26, and power slide 28 is depressed by bail 20 to engage end 95 of key operating lever 25, whereupon latch 27 by a spring 45 reengages its notch in slide 28, thus locking the slide in its depressed position and locking the key operating lever 25 in its position shown. The 10 complete operating cycle of code drum 39 now takes place, as described above for transmission under control of key 60 when manually depressed, and at the end of that complete operating cycle, the key 60 is unlocked as before. It will be noted 15 too, that keys 1 are locked against operation in the same manner and for the same reasons set forth in connection with the manual operation of key 60 so that the cyclic transmission controlled by code drum 39 may not be mutilated by any 20 key 1.

By the operation of the two keys at any station; namely, "figure shift" and "who-are-you," the transmission of line signals causes a response 25 in the receiving magnet of the inquiring station as well as in the receiving magnets of the remotely connected station. It is desired in this instance that the remotely connected station should respond with its identification signals but that the signature sending mechanism at the home station should not respond, thus leaving the home 30 station printing apparatus responsive to reverting control by the remotely connected station. It will be noted in such an instance that the operation of the "who-are-you" key at the inquiring 35 station results in the rotation of shaft 11, while the reception of the "who-are-you" code at the remotely connected station does not result in the rotation of shaft 11. Advantage is taken of this distinction to permit the remotely connected 40 station and non-rotated shaft 11 to respond to the "who-are-you" signal and to prevent the inquiring station with its rotated shaft 11 from responding to the "who-are-you" code. For this 45 purpose parts 16, 17, 18, 19, and 21 are provided.

Upon the operation of any key 1 clutch 10 operates and starts the shaft 11 which operates cam 15 to operate bail 14 which permits the lever 16 to rock upon its pivot 96 under the influence of spring 44 to rotate in turn the bell 50 crank lever 17 clockwise upon its pivot 97 to move the slide 18 forward, whereupon spring 100 connected from latch 19 to frame of the printer urges latch 19 to rock upon its fixed pivot 98 to engage a shoulder on slide 18 to retain slide 18 in its withdrawn or forward position so that lug 101 on pull bar stop member 21 will not be estopped from vertical movement by the end of slide bar 18. Lug 102 of member 21 is engaged and depressed by power bail 20 55 against tension of spring 103, but since the latching of bar 18 by latch 19, the rising of power bail 20 will permit stop member 21 to rise into position to block the selective movement of pull bar 22. Selector code bars 105 now align their notches in code combinations, to select the pull bar 22 both at the inquiring station and likewise at the remotely connected station, but at the inquiring station the operation of member 21 presents lug 104 in front of the end 106 of pull bar 22 so that pull bar 22 is estopped from responding to the code bar selection at the inquiring station, whereas at the remotely connected station members 16, 17, 18, 19, and 21 60

70 75 75

have not been operated and pull bar 22 is not estopped from responding to the code signal.

It follows then that at the remotely connected station there is a response of pull bar 22, rocking lever 26, latch 21, key operating lever 25, and multi-code key lever 29, whereas at the inquiring station the operation of stop member 21 causes pull bar 22 and accordingly lever 29 to remain unoperated. At the return movement of power bail 20, its engagement with lug 102 restores member 21 to its lower position against the tension of spring 103. While in its upper position, lug 101 has engaged latch 19 and has lifted the tooth of latch 19 out of engagement with the shoulder of slide bar 18, permitting slide bar 18 to move slightly to engage lug 101 under power of spring 107, and then by descent into its lower position lug 102 has removed itself from the path of slide bar 18, and slide bar 18 again takes its normal or rearward position, thus all parts are again normal in the inquiring station and the inquiring station is in condition to be fully responsive to the multi-code signal which the remotely connected station now has been conditioned to send.

It is obvious that this invention may be applied in variant manners to automatic telegraph transmitters and receivers of variant designs. Therefore the appended claims are not intended to be limited by the specific design here shown which is applicable to a specific transmitter and receiver but are intended to embrace the full range of equivalents when this invention is modified in mechanical interpretations to conform to other types of automatic telegraph machines.

What is claimed is:

1. In a telegraph transmitter, a plurality of character keys, means common to said keys to transmit a code signal representing a single character in response to one operation of a key, a further key, and means cooperating with said means to transmit a plurality of code signals representing a plurality of characters in response to one operation of said further key.

2. In a telegraph transmitter for operation at a station in a telegraph system, a plurality of character keys, means to transmit one code signal representing a single character in response to one operation of a key, a further key, and means to transmit a plurality of code signals in response to one operation of said further key, said plurality of code signals representing a plurality of characters identifying said station.

3. In a telegraph transmitter, a plurality of character keys, means to transmit code signals each representing a single character in response to one operation of a key, a further key, and means to transmit a plurality of said code signals representing a plurality of characters in response to one operation of the further key.

4. In a telegraph machine, a selecting mechanism, an operating element selectable by said mechanism, a transmitting mechanism for transmitting code combinations of impulses, a manually operable key lever, means actuated upon the operation of said key lever to cause said transmitting mechanism to transmit a plurality of code combinations of impulses, and means associated with said element and said key lever to operate said key lever in response to operation of said element.

5. In a telegraph transmitter, a plurality of character keys, means to transmit a code sig-

nal representing a single character in response to one operation of one of said keys, a further key, mechanism set into action by said further key to transmit a plurality of said code signals representing a plurality of characters in response to one operation of the key, and signaling mechanism responsive to a received code signal and controlling also the setting of said mechanism into action.

6. In a telegraph transmitter, a plurality of character keys, means to transmit a code signal representing a single character in response to one operation of a key, a further key, means to transmit a plurality of code signals representing a plurality of characters in response to one operation of said further key, and mechanism controlled by said further key to lock said character keys continuously during the extended period of transmission of a plurality of code signals representing a plurality of characters.

7. In a telegraph transmitter, single character key levers, means including code latches and code bars responsive to operation of one of said single-character key levers and effective to lock all others of said single-character key levers, a multi-character key lever, and further means including said code latches and said code bars and responsive to operation of said multi-character key lever and effective to lock all of said single character key levers.

8. In a telegraph transmitter, single-character keys, a multi-character key, means responsive to operation of said multi-character key and effective to transmit a plurality of code signals and to lock said single-character key levers, and further answerback means responsive to a received code signal and including said first mentioned means.

9. In a telegraph transmitter, a plurality of single-character key levers, a plurality of code bars controlled directly by said key levers for transmitting a single code signal in response to operation of one of said single-character key levers, a multi-character key lever, and means adapted to transmit a plurality of code signals representing a plurality of characters in response to one operation of said multi-character key lever and indirectly controlling said code bars for locking purposes only.

10. In a telegraph transmitter, a plurality of single-character key levers, a plurality of contacts associated with individual operating levers and a common transmission circuit, a plurality of contact-controlling members controlled by said single-character key levers and controlling said contacts to transmit a single code signal in response to operation of one of said single-character key levers, a multi-character key lever, and a plurality of further contact-controlling members controlled by said multi-character key lever and controlling said contacts to transmit a plurality of code signals representing a plurality of characters in response to one operation of said multi-character key lever.

11. In a telegraph transmitter, a plurality of single-character keys, a continuously operative power shaft, a start-stop member, a clutch connecting said shaft and said member, a clutch controlling member, a clutch operating member controlled by one of said single-character keys and effective to operate said clutch controlling member during a time period less than the time of one revolution of said start-stop member, a multi-character key, and a clutch operating member controlled by said multi-character key and effec-

- tive to operate said clutch controlling member during a time period greater than the time of one revolution of said start-stop member.
12. In a telegraph transmitter, a plurality of contacts associated with a transmission line, a set of single-code contact-controlling members, a set of multi-code contact-controlling members, and a further control member associated with said multi-code contact-controlling member and operable jointly therewith and effective to disable said set of single-code contact-controlling members. 5
13. In a telegraph transmitter, a motor, a rotary code signal transmitting member driven thereby, a rotary code signal control member, a driving pawl for said control member and operable by said transmitting member to drive said control member in stepping manner at each revolution of said transmitting member, a key and mechanical parts operated thereby to start said transmitting member and thereby said control member, a latch engaging said key parts to hold said key in depressed position, and a cam on said control member engaging said latch to control 10 said latch to retain said key in depressed position while said control member is in any code signal controlling position.
14. In a telegraph transmitter, electrical transmitting contacts, operating members for said contacts, key controlled latches engaging said operating members in code manner, a multi-code controller also engaging said operating members in code manner, and a multi-character key and associated mechanical parts engaging said multi-code controller to start said controller into rotation and engaging said key controlled latches to prevent them from engaging said operating members. 15
15. In a telegraph transmitter, multi-code transmitting mechanism, a key engaging said mechanism and operative when depressed to start said mechanism into automatic operation, a lever engaging said key to depress said key, case shift mechanism, and a latch operated by said case shift mechanism and effective to restrain said lever when said case shift mechanism is in one case position and to clear said lever when said case shift mechanism is in another case shift position. 20
16. In a telegraph transmitter, a motor shaft, electrical signal transmitting contacts, a manual key and a key lever and associated mechanical parts engaging said contacts and controlling said contacts and said motor shaft to transmit in code manner when said key lever is operated, a power driven member and associated mechanical parts responsive to a predetermined received code signal combination of electrical impulses to cause said motor to drive said member, mechanical parts engaging said power driven member and 25
- said key lever and effective to operate said key lever as a result of operation of said power driven part, and an interfering member controlled by said key lever and associated mechanical parts and effective when so controlled to engage said power driven member in a manner to disable said member for a limited time from response to said code signal. 30
17. In a telegraph transmitter, a plurality of transmitter keys, a pull bar, a further transmitter key mechanically associated with said pull bar and controllable thereby, and a member mechanically associated with said plurality of keys and operable thereby to engage said pull bar to estop operation of said pull bar. 35
18. In a telegraph transmitter, a key, power members associated with said key for operating said key in response to a predetermined code signal when received, a further key and mechanical parts and electrical contacts associated therewith for completing said predetermined signal, and a mechanical member associated with said further key and effective under control of said further key to prevent operation of said first mentioned key in response to said further key. 40
19. In a telegraph apparatus having a transmitter and a receiver, a rotary signal-generating member in the transmitter, a cyclic mechanical member in the receiver, means in said receiver operable in response to signals generated by said rotary member, a selectable member controlled by said means in said receiver and operable by said cyclic member following its selection, and means to prevent operation of said selectable member settable by said rotary member and restorable 45 by said cyclic member. 45
20. In a telegraph apparatus, a transmitter, a receiver, a mechanical member in said receiver, means in said receiver operable in response to signals generated by said transmitter, a selectable member controlled by said means and operable by said mechanical member following its selection, and means to prevent operation of said selectable member settable by said transmitter and restorable 50 by said mechanical member. 50
21. In a response-signal telegraph apparatus, a transmitter, a response-asking key in said transmitter, means in said transmitter operated in accordance with the operation of said key for transmitting signal impulses, a receiver, a response-controlling selectable member in said receiver, means in said receiver responsive to said impulses for selecting said member, a mechanical member settable by said response-asking key for obstructing operation of said response-controlling selectable member, and means in said receiver for restoring said mechanical member to its normal position. 55

KARL WEBER.
